UNITED STATES PATENT OFFICE.

ROSCOE W. PROUT AND REGIS C. PROUT, OF DENVER, COLORADO.

TRAFFIC SIGNAL.

Application filed June 28, 1923. Serial No. 648,391.

This invention relates to signals such as are used for automobiles, and the like, and is essentially a traffic warning signaling device. It is to be understood that while the invention is especially adapted for use in connection with automobiles, it may also be used at railroad and highway crossings, and at intersecting streets, and other like places where it is desirable to provide a signal capable of giving a variety of warning indications.

One important object of the invention is to improve the general construction of devices of this character.

15 A second important object of the invention is to provide an improved magnetic control for devices of this character.

A third important object of the invention is to provide a signal of improved and novel construction wherein the positioning and displaying of the signal indications may be controlled from a remote station, as for instance, the signal may be placed on the rear of an automobile, and the control on the steering post, or the signal may be placed at a street intersection and the control at a remote point under the care of the traffic officer.

20 A fourth important object of the invention is to provide a novel means for automatically selecting the signal to be displayed and positioning the same for display.

25 A fifth important object of the invention is to provide a novel means for restoring the signal to its initial or neutral position.

With the above and other objects in view as will be hereinafter apparent, the invention consists in general of certain novel details of construction and combinations of parts hereinafter to be fully described, illustrated in the accompanying drawings, and specifically claimed.

In the accompanying drawings like characters of reference indicate like parts in the several views, and:

Fig. 1 is a view partly in section and partly in elevation showing the various parts of the device in their assembled relation, the view being partly on the line X—X of 30 Fig. 2.

Fig. 2 is a transverse section through the device showing a portion of the operating features thereof, the features behind those

shown being omitted for the sake of clearness in illustration. 55

Fig. 3 is a detail section on the line 3—3 of Fig. 1.

Fig. 4 is a side elevation of certain parts shown in detail in Fig. 3.

Fig. 5 is a detail view of certain contact making and breaking mechanisms. 60

Fig. 6 is a detail of certain other contact making and breaking mechanisms.

Fig. 7 is a detail section through the signal or display prism, the section being taken 65 on the line 7—7 of Fig. 1.

Fig. 8 is a detail end view partly broken away and partly in section.

Fig. 9 is a detail view of certain connections and contacts used herewith. 70

Fig. 10 is a general diagrammatic view of the entire device showing the wiring thereof.

The particular embodiment of the device herein disclosed has been illustrated as covering an automobile signal having five positions so that there may be a condition of the signal corresponding to normal running condition of the machine, a second condition indicating a right turn, a third condition indicating a left turn, a fourth condition indicating a back, and a fifth condition indicating slow. It is of course obvious that the indications will depend on the wording or lettering of the signals, and may be used for any other characters of signals 85 within the range of the device. It will also be apparent that the construction may be varied so that less or more signals may be actuated in the same manner. 80

In a five position signal of this kind for 90 automobiles, there is provided at any convenient place near the driver's seat, a series of push buttons or contacts, and in the present instance, by reference to Fig. 10, these contacts will be seen at the top of the 95 figure. It will there be noted that there is a contact 11, which is used for the left turn indication, a contact 12 used for the slow indication, a contact 13 used for restoring the various parts to the central position or normal condition, a contact 14 used in indicating a back, and a contact 15 used in indicating the right turn. Within a suitable casting 16, there is provided a pair of magnets 17 and 18, the magnet 17 having the left 100 rotary magnet and the magnet 18 having the 105

right rotary magnet, preferably so-called. Between these magnets there is journalled a shaft 19 and the magnet cores are formed with inclined ends 20 so that an armature 21 fixed on the shaft 19 may oscillate between these two magnet cores in accordance with the energization of one or the other of the rotary magnets. Also fixed on this shaft 19 is a segmental gear 22 which meshes with a pinion 23 fixed upon a shaft 24 supporting an internally illuminated signalling prism 25 having, in the present instance, five transparent or partly transparent sides bearing suitable signal indicia not deemed necessary here to be shown, as such is common in the art.

This prism is positioned so that in giving any signal one flat side of the prism will be exposed through a window 26 formed in the casing 16. Fixed upon the shaft 24 is a disk 27 having a projecting lug 28 which normally lies vertically beneath the shaft 24 and is held therefrom accidental rotation by a pair of pawls 29 which are pivoted to the pole pieces of the cores of the magnets 18 and 17, and are yieldably held in position by a spring 30 which connects these two pawls, as can be clearly seen in Fig. 2. Now it will be observed that under these conditions if, for instance, the magnet 18 be energized, the corresponding pawl 29 will be attracted by the pole piece of the magnet, this being off-set and shaped for this position, and the pawl being of magnetic material, such as iron. This will effect release of the disk 27 so that it may be turned and since the energization of the magnet 18 has attracted the armature 21 partial rotation of the shaft 19 will take place, and this in turn will effect movement of the segmental gear 22 and constant rotation of the shaft 24 and signal prism.

Certain devices are used which control the extent of this rotation, and similarly other devices are used which restore the armature 21 to its central position and consequently restore the prism to neutral. In this connection by reference to Fig. 3, it will be seen that upon the segmental gear 22 is provided a pair of arms 31, which are pivoted to the segment adjacent the shaft 19 as shown at 32. These arms are drawn toward each other by means of a spring 33, but are prevented from approaching beyond a certain limit by a stop member 34. Furthermore, between these arms are positioned certain stop pins 35 which are supported on a frame member 36 within the casing. Now, under these conditions, let it be supposed that the segment 22 in Fig. 3 is, by proper action of one of the rotary magnets swung to the right. The stop member 34 will cause the right hand arm 31 to swing to the right with the segment, while at the same time movement in that direction of the left hand arm 31 will

be prevented by the engagement of said arm with the stationary stop pin 35. Consequently, the spring 33 will be tensioned, and will tend to restore the segment 22 to its central position, as shown in Fig. 3. If no means be provided to lock the segment in shifted position, then as soon as the magnets, which cause the movement of the segment 22 is deenergized, the spring 33 will draw the arms 31 toward each other, and since one of these arms is substantially fixed the right hand arm will move and restore the segment. At the side of each magnet pole piece is pivoted an armature lever 37, which, when the magnet is energized is attracted by the pole piece, and this lever is normally held away from the pole piece by means of a suitable spring 38.

Furthermore, the lever carries a contact member 39 engageable with a fixed contact 40. This apparatus just described I preferably call the first position locking contact device. The disk 27 is preferably termed the selector cam, and adjacent each side of this disk is a shaft 41 which carries a selector pawl 42. These pawls are normally kept in such position by means hereinafter to be described that the lug 28 will be engaged by one of the pawls, so that the rotation of the disk 27, and consequently of the shaft 24 is limited. However, each of the shafts 41 also carries an armature 43 which is positioned to be attracted by the pole piece of a magnet 44 under certain conditions so that the respective pawl 42 may be drawn away from the disk 27 and thus allow the lug 28 to pass freely beyond the pawl 42. Above each of the shafts 41 is a second shaft 45 and fixed on each of these shafts is a holding pawl 46 which bears on a holding cam or disk 47 fixed on the shaft 24, and provided with spaced lugs or projections 48.

It will be observed from Fig. 2 that the ends of the pawls 46 are positioned and close together, but sufficiently far apart to permit a respective lug 48 to drop in between them. Now suppose the conditions are such that both the magnets 18 and the right hand magnet 44 are energized, then a rotation of the shaft 24 will be set up which will bring the right hand lug 48 between the ends of the pawls 46, this being a second position for the shaft 24, and consequently for the signal. On the shaft 41 and 45 are fixed arms 49 which are connected by springs 50 so that these springs serve to hold the pawls 46 and 42 in engagement with their respective disks. Of course, under these conditions, means must be provided for releasing the pawls 46 to permit the disk 47 to rotate backwards, and in order to do this, there is provided what we preferably term a centering magnet 51, which is located between the shafts 45, and which has a core projecting at

both ends, thus forming pole pieces for swinging armatures 52 fixed on the shaft 45.

Thus the energization of the magnet 51 will lift the pawls 46 and free them from engagement with the respective lug 48 so that the spring 33 can act to restore the parts to their normal position. Now, it is to be noted, that with the apparatus here shown, provision is made, first for a normal position in which the disks or cams and all parts are shown in Fig. 2. After this provision is made, where rotation in either direction of the disk 27 through either one-fifth of a circle or through two-fifths of such circle, so that there are thus five separate and distinct positions which can be assumed by the shaft 24, and consequently, by the signal prism.

Now considering the wiring of the entire device, and referring especially in this connection to Fig. 10, it will be seen that there is provided the ordinary automobile battery B, one terminal of which is grounded as at G. From the remaining terminal of the battery B leads a main line wire 53, which is controlled by a main switch or release switch 54. Branches 55 connect this main line wire with the several push buttons 11 to 15 inclusive. From the push button 11 extends a wire 56 which leads to the winding of the magnet 17, and from thence through a wire 57 to a ground 58. Similarly, from the push button 15, a wire 59 leads to the winding of the magnet 18 and thence through a wire 60 to the ground 58. From the push button 12, a wire 61 leads to the winding of the left hand selector magnet 44, and from thence through a wire 62 to the wire 56 so that depression of the push button 12 connects the magnets 44 and 17 in series. Similarly, from the push button 14 a wire 63 leads to the winding of the right hand selector magnet 44, and from thence through a wire 64 to the wire 59 so that depression of the push button 14 connects the right hand selector magnet and the rotary magnet 18 in series. From the push button 13, a wire 65 leads to the winding of the magnet 51 and from thence through a wire 66 to a circuit closure 67 connected to the ground as at 68. At 69 is shown the brake lever of the automobile, and this lever is connected by a wire 70 with the main line 53, and forms one element of a circuit closure, the other element of which is connected by a wire 71 with the wire 61 so that upon movement of this brake lever in one direction, circuit is closed through the left hand selector magnet 44 and the magnet 17. Similarly at 72 is the gear shift lever which is connected by a wire 73 with the main line 53, and forms one element of the circuit closure, the other element of which is connected by a wire 74 with the wire 63. At 75 is a steering shaft, and on this shaft is mounted the usual steering wheel 76, which is here shown, for

convenience in illustrating the diagram, as formed of two parts. This steering wheel is provided with a lug 77 which controls a circuiting closing lever 78, so that when the lever is moved in one direction it closes a circuit through the wire 79 connected to the main line wire 53 and the lever, and thence through a wire 80 connected to the wire 56. Thus, under these conditions, the magnet 17 will be energized. Under other conditions, the lever 78 closes a circuit through a wire 81 which is connected to the wire 65 leading to the magnet 51. Also a contact 82 is positioned to be engaged by the lever 69 under normal conditions, and is connected to said wire 81. A second lug 83 on the steering wheel controls a contact lever 84, which is connected by wire 85 to the main line wire 53, and oscillates between a pair of contacts, one of which is connected by wire 86 with the wire 59 to close a circuit through the magnet 18, and the other of which is connected by wire 87 with the wire 65, and thus through the magnet 51.

Furthermore, a contact 88 is connected to this wire 87 and is engageable under normal conditions by the lever 72. Leading from the main line wire 53 is a wire 89, which is wound around a relay magnet 90, and from thence leads, by means of a wire 91, to the signal lamps 92, these lamps being connected in parallel and being also connected by a wire 93 with the wire 96. The armature of this relay magnet is shown at 94, and from the wire 89 extends a branch 95, which leads through an indicator lamp 96, and thence to the armature 94, a contact 97 being positioned to be engaged by the armature 94 upon energization of the magnet 90, this contact being grounded as at 98. From the wire 91 extends a branch 99 which leads to a lever 100, pivoted adjacent the segment 22, and normally held in contact with a cam 101 fixed on said segment by means of a spring 102. Adjacent this lever is a fixed contact 103, which is connected by a wire 104 with a movable contact member 105 oscillating between fixed contacts, one of which is connected by wire 106 with the wire 63, while the other is connected by wire 107 with a movable contact 108. This latter contact in turn oscillates between fixed contacts, one of which is connected by a wire 109 with the wire 61, while the other is connected by wire 110 with a movable contact member 111 engaging a contact 112 which is connected by wire 113 to a bridge wire 114 connecting the arms 37.

From the wire 53 leads a wire 115 which passes through a switch 116 and through the tail lamp 117. From thence this wire leads to a lever 118 controlled by a cam 119 on the segment 22 and removable to engage and disengage from a contact 120 connected by wire 121 to the ground 122. A branch wire 123

123 leads from the wire 115 through a backing lamp 124 to the vertical sector contacts and thence to the ground 125.

At this point it is now deemed advisable to explain the operation of the device, and to this end, by reference to the wiring diagram, it will be seen that there is provided certain manually operated push buttons, automatically operating the contacts and connections from there to the working parts of the device. Assuming, for instance, that the operator wishes to show the signal to the position indicating a right hand turn. The operator depresses the proper button on the steering wheel. This energizes the right hand rotary magnet, and accordingly pulls the right hand centering pawl free of the lug on the selecting cam or disk, which leaves the signal shaft free to turn in the desired direction; at the same time the rotary magnet operates the rotary armature and the first position locking contact armature. Accordingly this signal turns to one-fifth of a revolution. When the signal has turned one-fifth of the revolution, the selector cam operates to stop further turning and the holding pawl has dropped behind the first lug on the holding cam. In the event that the driver or operator does not keep the button contact closed sufficiently long to complete operation of the signal, it will be seen that the instant the rotary magnet is energized, the first position circuit closer is closed, and this establishes a locking circuit through the left hand contacts controlled by the cams on the sector, which contact is maintained until sufficient movement has taken place in the sector to again break these circuits. Similarly, the instant the movement of the sector starts the upper lever is resting on the upper sector cam and operates to light the interior lamps in the interior of the signal as the movable arm is allowed to drop, and to close this circuit. At the same time, if the tail lamp is burning the upper sector cam will raise the upper right hand contact arm and break this circuit.

It is to be noted that in making this turn, the driver has shifted his steering wheel, and when he straightens up after the turn has been made, the circuit is automatically closed through the centering magnet which releases these parts. As in the other case, provision is made for closing a locking circuit through the centering magnet, and the detail construction of the locking circuit closing device is clearly shown in Fig. 6 wherein there is shown on the right hand shaft 45, an arm 126 which is positioned to engage a lever 127 connected by wire 128 with the wire 53, the lever 127 being engageable with a contact connected by wire 129 to the wire 81. Here it is desired to state that in Fig. 9, will be seen certain cable connecting blocks 130, and

arrangement of spring pressed contact members 131 for connecting the various circuits in the casing.

As previously described, when it is desired to move the signals through to two-fifths of a circle, the operation is such as to connect the magnets on the proper side in series, and it will be obvious that the holding circuits will be operated in like manner as before.

There has thus been provided a simple and efficient device of the kind described and for the purpose specified.

It is obvious that minor changes may be made in the form and construction of the invention without in any way departing from the material spirit thereof. It is not, therefore, desired to confine the invention to the exact form herein shown and described, but it is desired to include all such as properly come within the scope claimed.

Having thus described the invention, what is claimed as new, is:

1. In a device of the kind described, a rotary signaling member having signal indicia placed around its periphery, electromagnetic means operable by the closing of a circuit for causing said member to rotate, a locking device including said electromagnetic means normally holding said member in neutral position and operable to move to released position upon energization of the said electromagnetic means, other electromagnetic means controlling the extent of said rotation, spring means urging the signaling means to normal position, and an electromagnetic locking mechanism holding the signal releasably against actuation by said spring means.

2. In a signaling device, a rotary signaling element, electromagnetic means to rotate the signal in either direction, including a pair of magnets, and means including a pair of pawls of magnetic material normally holding said element against rotation and controlled by said magnets to release the element for rotation in one direction upon energization of one of said magnets and in the other direction upon energization of the other magnet, the pawl adapted to be controlled by the unenergized magnet remaining quiescent and acting as a stop upon return of the rotary member to neutral position.

3. In a signaling device, a rotary signaling element, electro-magnetic means to rotate the signal in either direction, including a pair of magnets, means normally holding said element against rotation and controlled by said magnets to release the element for rotation in one direction only upon energization of a respective magnet, and comprising a disk rotatable with the element and having a lug projecting therefrom, a pair of pawls of magnetic material normally engaging said lug and arranged each to be

5 moved to release position by a respective magnet, and means to limit the rotation of said element including a pair of stop pawls arranged on opposite sides of the disk in the path of said lug.

4. In a signaling device, a rotary signaling element, electro-magnetic means to rotate the signal in either direction, including a pair of magnets, means including a pair of pawls of magnetic material normally holding said element against rotation and controlled by said magnets to release the element for rotation in one direction only upon energization of one of said magnets and in the other direction upon energization of the other magnet, the pawl adapted to be controlled by the unenergized magnet remaining quiescent and acting as a stop upon return of the rotary member to neutral position, electro-magnetically releasable holding means for holding said element in its rotated position, and spring means for restoring the element to normal position upon release.

25 5. In a signaling device, a rotary signaling element, electro-magnetic means to rotate the signal in either direction, including a pair of magnets, means including a pair of pawls of magnetic material normally holding said element against rotation and controlled by said magnets to release the element for rotation in one direction upon energization of one of said magnets and in the other direction upon energization of the other magnet, the pawl adapted to be controlled by the unenergized magnet remaining quiescent and acting as a stop upon return of the rotary member to neutral position, said holding means also including a disk rotatable with the element and having a lug projecting therefrom, said pawls normally engaging said lug and arranged each to be moved to release position by a respective magnet, electro-magnetically releasable holding means for holding said element in its rotated position, and spring means for restoring the element to normal position upon release.

6. In a signaling device, a rotary signaling element, electro-magnetic means to rotate the signal in either direction, including a pair of magnets, means including a pair of pawls of magnetic material normally holding said element against rotation and controlled by said magnets to release the element for rotation in one direction upon energization of one of said magnets and in the other direction upon energization of the other magnet, the pawl adapted to be controlled by the unenergized magnet remaining quiescent and acting as a stop upon return of the rotary member to neutral position, means to limit the rotation of said element, electro-magnetically releasable holding means for holding said element in

its rotated position, and spring means for restoring the element to normal position upon release.

7. In a signaling device, a rotary signaling element, electro-magnetic means to rotate the signal in either direction, including a pair of magnets, means including a pair of pawls of magnetic material normally holding said element against rotation and controlled by said magnets to release the element for rotation in one direction only upon energization of a respective magnet, said holding means also including a disk rotatable with the element and having a lug projecting therefrom, said pawls normally engaging said lug and arranged each to be moved to release position by a respective magnet, means to limit the rotation of said element including a pair of stop pawls arranged on opposite sides of the disk in the path of said lug, electro-magnetically releasable holding means for holding said element in its rotated position, and spring means for restoring the element to normal position

8. In a signaling device, a rotary signaling element, electro-magnetic means to rotate the signal in either direction, including a pair of magnets, means including a pair of pawls of magnetic material normally holding said element against rotation and controlled by said magnets to release the element for rotation in one direction only upon energization of a respective magnet, said holding means also including a disk rotatable with the element and having a lug projecting therefrom, said pawls normally engaging said lug and arranged each to be moved to release position by a respective magnet, means to limit the rotation of said element including a pair of stop pawls arranged on opposite sides of the disk in the path of said lug, and electro-magnetic means for releasing the stop pawls.

9. In a signaling device, a rotary signaling element, electro-magnetic means to rotate the signal in either direction, including a pair of magnets, means including a pair of pawls of magnetic material normally holding said element against rotation and controlled by said magnets to release the element for rotation in one direction only upon energization of a respective magnet and said holding means also including a disk rotatable with the element and having a lug projecting therefrom, said pawls normally engaging said lug and arranged each to be moved to release position by a respective magnet, means to limit the rotation of said element including a pair of stop pawls arranged on opposite sides of the disk in the path of said lug, electro-magnetic means for releasing the stop pawls including a pair of magnets in series with the first mentioned magnets.

10. In a signaling device, a rotary signaling element, electro-magnetic means to rotate the signal in either direction, including a pair of magnets, means including a pair of pawls of magnetic material normally holding said element against rotation and controlled by said magnets to release the element for rotation in one direction only upon energization of one of said magnets and in 10 the other direction upon energization of the other magnet, the pawl adapted to be controlled by the unenergized magnet remaining quiescent and acting as a stop upon return of the rotary member to neutral position, and said holding means also including a disk rotatable with the element and having a lug projecting therefrom, said pawls normally engaging said lug and arranged each to be moved to release position 20 by a respective magnet, means to limit the rotation of said element including a pair of stop pawls arranged on opposite sides of the disk in the path of said lug, electro-magnetic means for releasing the stop pawls, electro-magnetically releasable holding means for holding said element in its rotated position, and spring means for restoring the element to normal position upon release.

11. In a signaling device, a rotary signaling element, electro-magnetic means including a pair of pawls of magnetic material to rotate the signal in either direction, including a pair of magnets, means normally holding said element against rotation and controlled by said magnets to release the element for rotation in one direction only upon energization of a respective magnet, said holding means also including a disk rotatable with the element and having a lug projecting therefrom, said pawls normally engaging said lug and arranged each to be moved to release position by a respective magnet, means to limit the rotation of said element including a pair of stop pawls arranged on opposite sides of the disk in the path of said lug, electro-magnetic means for releasing the stop pawls including a pair of magnets in series with the first mentioned magnets, electro-magnetically releasable holding means for holding said element in its rotated position, and spring means for restoring the element to normal condition upon release.

12. In a signaling device, a rotary signaling element, electro-magnetic means to rotate the signal element in either direction including a pair of magnets, means normally holding said element against rotation and controlled by said magnets, said holding means including a pair of pawls of magnetic material each forming the armature of a respective magnet and moved thereby to release position, said holding means further including a disk rotatable with the element and having a lug normally held between said

pawls, electro-magnetically controlled means for holding the element releasably in rotated position and including a second disk rotatable with the signaling element and having a plurality of lugs thereon, said last means also including a pair of pawls arranged on opposite sides of the second disk to engage respective lugs thereon, said means further including a centrally disposed bar electro-magnet and a pair of armatures therefor each of which has operative connection with a respective pawl of the last mentioned pair, and spring means for restoring the element to normal position upon release by the last mentioned holding means. 80

13. In a signaling device, a rotary signaling element, electro-magnetic means to rotate the signal element in either direction including a pair of magnets, means normally holding said element against rotation and controlled by said magnets, said holding means including a pair of pawls of magnetic material each forming the armature of a respective magnet and moved thereby to release position, said holding means further including a disk rotatable with the element and having a lug normally held between said pawls, electro-magnetically controlled means for holding the element releasably in rotated position and including a second disk rotatable with the signaling element and having a plurality of lugs thereon, said last means also including a pair of pawls arranged on opposite sides of the second disk to engage respective lugs thereon, said means further including a centrally disposed bar electro-magnet and a pair of armatures therefor each of which has operative connection with a respective pawl of the last mentioned pair, and spring means for restoring the element to normal position upon release by the last mentioned holding means. 90

14. In a signaling device, a rotary signaling element, electro-magnetic means to rotate the signal element in either direction including a pair of magnets, means normally holding said element against rotation and controlled by said magnets, said holding means including a pair of pawls of magnetic material each forming the armature of a respective magnet and moved thereby to release position, said holding means further including a disk rotatable with the element and having a lug normally held between said pawls, electro-magnetically controlled means for holding the element releasably in rotated position and including a second disk rotatable with the signaling element and having a plurality of lugs thereon, said last means also including a pair of pawls arranged on opposite sides of the second disk to engage respective lugs thereon, said means further 100

15. In a signaling device, a rotary signaling element, electro-magnetic means to rotate the signal element in either direction including a pair of magnets, means normally holding said element against rotation and controlled by said magnets, said holding means including a pair of pawls of magnetic material each forming the armature of a respective magnet and moved thereby to release position, said holding means further including a disk rotatable with the element and having a lug normally held between said pawls, electro-magnetically controlled means for holding the element releasably in rotated position and including a second disk rotatable with the signaling element and having a plurality of lugs thereon, said last means also including a pair of pawls arranged on opposite sides of the second disk to engage respective lugs thereon, said means further 110

110

120

130

including a centrally disposed bar electro-magnet and a pair of armatures therefor each of which has operative connection with a respective pawl of the last mentioned pair, 5 spring means for restoring the element to normal position upon release by the last mentioned holding means, and releasable means to limit movement of the under element under influence of the electro-magnetic rotating means in either direction, said last means including a pair of pawls on opposite edge portions of said first disk in the path of the lug on said first disk, and a second pair of electro-magnets each associated with 10 a respective last mentioned pawl and having an armature operatively connected thereto. 15. In a signaling device, a rotary signaling element, electro-magnetic means to rotate the signal element in either direction including a pair of magnets arranged in opposed aligned relation and having an armature common to both and operatively connected to the signaling element, means normally holding said element against rotation and controlled by said magnets, said holding means

including a pair of pawls of magnetic material each forming the armature of a respective magnet and moved thereby to release position, said holding means further including a disk rotatable with the element and having 30 a lug normally held between said pawls, electro-magnetically controlled means for holding the element releasably in rotated position and including a second disk rotatable with the signaling element and having a plurality of lugs thereon, said last means also including a pair of pawls arranged on opposite sides of the second disk to engage respective lugs thereon, said means further including a centrally disposed bar electro- 35 magnet and a pair of armatures therefor each of which has operative connection with a respective pawl of the last mentioned pair, and spring means for restoring the element to normal position upon release by the last 40 mentioned holding means.

In testimony whereof we affix our signatures.
